(57) **CLAIM**

The ornamental design for a distribution robot, as shown and described.

DESCRIPTION

1.1 is a front view of a distribution robot;
1.2 is a back view thereof;
1.3 is a left view thereof;
1.4 is a right view thereof;
1.5 is a top view thereof;
1.6 is a perspective view thereof;
1.7 is another perspective views thereof;
2.1 is a front view of a distribution robot;
2.2 is a back view thereof;
2.3 is a left view thereof;
2.4 is a right view thereof;

(Continued)

2.5 is a top view thereof;
2.6 is a perspective view thereof; and
2.7 is another perspective views thereof.

1 Claim, 9 Drawing Sheets
